GOLF CLUB HEAD

John S. Palmer, Clarendon Hills, Ill.

Application June 17, 1959, Serial No. 56,403

Term of patent 14 years

(Cl. D34—5)

Figure 1 is a front elevational view of the golf club head showing my new design.

Figure 2 is a top view of the golf club head of Figure 1. Figure 3 is a rear view of the golf club head of Figure 1.

Figure 4 is a bottom view of the golf club head.

Figure 4 is a bottom view of the golf club head. Figure 5 is an elevational view of one end of the golf club head.

Figure 6 is an elevational view of the other end of the golf club head.

Figure 7 is a sectional view taken on the line 7—7 of Figure 3.

Figure 7 is a sectional view taken of Figure 3.

The fragmentary broken line showings of a club shaft in Figs. 1, 3, 5 and 6 are for illustrative purposes only.

In Figs. 1,

I claim:
The ornamental design for a golf club head, as shown
and described.
